Robert Young Inventor
By Attorney

UNITED STATES PATENT OFFICE.

LESTER F. BIRD, OF SEATTLE, WASHINGTON.

INDUCTANCE.

Application filed January 5, 1921. Serial No. 435,271.

To all whom it may concern:

Be it known that I, LESTER F. BIRD, a citizen of the United States, residing at Seattle, in the county of King and State of Washington, have invented certain new and useful Improvements in Inductances, of which the following is a specification.

This invention relates to inductances. An object of the invention is to provide a simple and compact arrangement of inductance coils for interconnected circuits and including coils in inductive relation with one another whereby the inductance of such circuits is varied and the ratio of transformation also varied as desired.

My invention is applicable to other forms of electrical inductances for the purpose of varying the total inductance of any circuit and the ratio of transformation.

20 Further features and objects of the invention will be more fully understood from the following detailed description and the accompanying drawings, in which—

Fig. 1 is a side elevation of an embodiment of the invention applicable for radio sets; and

Fig. 2 is a diagram, on a somewhat reduced scale, of the same.

The form of the invention illustrated in the drawings is particularly adapted for a radio transmitting set in which the outer coil 1 is the antenna coil, the innermost coil 2 is connected to the plate of the vacuum tube oscillator and the upper coil 3 is connected to the grid of the vacuum tube oscillator. The coil 1 is formed of the required number of turns of the desired wire and wound on a suitable insulating base whose inner, cylindrical base makes a snug friction fit with the outer face of coil 2. In Fig. 2 I have indicated diagrammatically the windings 4, of the antenna coil 1 and the hollow or tubular base 5 of insulating material on which the windings 4 are mounted.

The direction of winding of the windings 4 may be counterclockwise as viewed from above.

The coil 2 is similarly constructed and comprises the desired number of turns indicated at 6 in Fig. 2, and mounted on a

suitable base 7 of insulating material. Such coil 6 may be wound in counter clockwise direction, as viewed from above.

Coil 3 is wound similarly of suitable windings 8 mounted on a suitable base 9 of insulating material. The insulating bases 7, 9, may be separate from one another and secured together, or the bases 7, 9, may be integral and formed of the different diameters as indicated.

Preferably, the winding 8 is continuous with the winding 6. Upon slipping the coil 1 relatively to the coil 2, in either direction parallel to the longitudinal axis of the cylindrical base 7, the inductive relation of the winding 4 relative to the winding 6 is varied and similarly the inductive relation of the winding 4 relative to the winding 8 is separately varied.

70 My invention is particularly applicable in radio transmitting sets, since, as I have discovered, such arrangement of the inductances for the grid and plate of the vacuum tube oscillator and the coil for the antenna mounted about the plate coil renders the output of the oscillations substantially constant notwithstanding that the wave length may be varied.

It will be noted that the invention provides for a compact mounting for the several inductances and permits of ready adjustment of the inductances to one another.

Whereas I have described my invention by reference to specific forms thereof, it will be understood that many changes and modifications may be made without departing from the spirit of the invention, as defined by the appended claim.

I claim,

90 In a radio set, an antenna coil, a hollow insulating base supporting said antenna coil, a plate coil disposed within said hollow base, a cylindrical base supporting said plate coil, said hollow base being frictionally held on said plate coil, a grid coil, and an insulating base for said grid coil said grid coil base having a fixed relation to said cylindrical base.

95 In testimony whereof I have affixed my 100 signature.

LESTER F. BIRD.
